UNITED STATES PATENT OFFICE.

LEON F. HIRSH, OF YORK, PENNSYLVANIA.

COVER-LIFTER FOR SHEET-METAL BOXES.

No. 870,513.

Specification of Letters Patent.

Patented Nov. 5, 1907.

Application filed May 16, 1907. Serial No. 374,066.

To all whom it may concern:

Be it known that I, LEON F. HIRSH, a resident of York, county of York, and State of Pennsylvania, have invented a new and useful Improvement in Cover-Lifters for Sheet-Metal Boxes, of which the following is a specification.

My invention belongs to that class of cover lifting devices, in which the cover lifter is pivotally connected to the box, and is adapted to operate against the edge of the cover for the purpose of lifting the same. Devices of this kind are not new.

My invention resides in the particular construction of the device whereby it may be cheaply and expeditiously made, and readily applied to the box.

15 The device is a key-like lever, consisting of three parts, a pivot, a finger piece by which the device is turned and a shouldered portion between the finger piece and pivot. All of these parts lie in the same plane, each on the prolongation of the other, and they 20 are fashioned in one piece from sheet steel, being cut out and shaped at one operation. The pivot is quite short—just long enough to pass through the side of the box, and to have its inner end upset or headed up, so as to hold the device in place. The shouldered portion 25 extends under the edge of the box cover in position to lift it when the key-like device is turned. And the finger piece, by which the turning movement is effected, protrudes as an extension from the outer edge of the shouldered portion.

30 The device can be readily and quickly applied to the box, at one operation, the pivot serving as a punch to force its own way through the side of the box and its protruding inner end being then headed up during the same movement. The form and construction of 35 the key-like lifter, permits of this way of applying and securing it in place.

The device is intended more particularly for use on boxes for containing shoe blacking or polish, and it is in this connection that I shall describe it.

40 In the accompanying drawings to which I shall now refer for a better understanding of my invention—Figure 1 is a view of the key-like cover lifter detached. Fig. 2 is a view showing the device as applied to a box, and in the position it occupies in lifting the cover. 45 Fig. 3 is a vertical axial cross section of the box and cover with the latter down, the line of section being axially through the cover lifter.

The device is struck out in one from a flat sheet of soft steel, and consists of the finger piece *a*, the pivot *b* and the intermediate shouldered strip or portion *c*.

These parts, as before said are formed in one, and lie flat in the same plane, one on the prolongation of the other, and the device as a whole is designed to stand at right angles with the wall of the box to which it is applied.

55

The box is lettered *A* and the cover *B*. The device is applied to the box by passing the pivot *b* through a hole in the side of the box, and then heading up or upsetting its inner end, this bringing the inner edge of the shouldered portion *c* up against the exterior of the 60 side wall of the box, the device being so located that the flat face of the shoulder portion lies just below and underneath the edge of the cover *B* when the latter is down. The edge of the cover may be, and preferably is, slightly flared as at *d*, so that it will more surely be 65 engaged by the shouldered portion *c* when the latter is turned on the pivot *b* as an axis. With the same end in view the annular bead *x* on the box, just below the point where the edge of the cover comes when closed, may be flattened, as at *e*, where it would otherwise meet 70 the part *c*—thus allowing the latter to get well underneath the edge of the cover. This flattening of the bead can be effected by and during the operation of attaching the key to the box.

75 The operation of the device will be understood without further explanation. Its action in that regard is not unlike that of cover lifters of the pivoted lever type heretofore known. What is essentially novel in it, so far as I am aware, is its special form and construction and its application to the box, as hereinbefore set forth.

80 I am aware that it is not new with me to provide a box with a lever-like cover lifter pivotally connected to the box and adapted to act against the edge of the cover to raise the same; and this I do not claim.

85 What I do claim herein as new and desire to secure by Letters Patent is—

In combination with the box and cover, the flat sheet metal key-like cover-lifter consisting of the finger piece *a*, the pivot *b*, and the intermediate shouldered strip *c* formed integral, the pivot *b* and finger piece *a* being located upon, and projecting from, opposite edges of the shouldered strip *c*, the device as a whole standing at right angles to the side of the box and connected thereto by the pivot *b* in position to permit its shouldered portion *c* to act against the edge of the cover in order to 95 lift the same, as hereinbefore shown and described.

In testimony whereof I affix my signature in presence of two witnesses.

LEON F. HIRSH.
